UNITED STATES PATENT OFFICE

151,007

DESIGN FOR A LAWN SPRINKLER

Corey L. Russell, Milwaukee, Wis.

Application February 17, 1947, Serial No. 136,949

Term of patent 14 years

(Cl. D91—1)

To all whom it may concern:

Be it known that I, Corey L. Russell, a citizen of the United States, residing at Milwaukee, in the county of Milwaukee and State of Wisconsin, have invented a new, original, and ornamental Design for a Lawn Sprinkler, of which the following is a specification, reference being had to the accompanying drawing, forming part thereof.

In the drawing:

Fig. 1 is a top plan view of a lawn sprinkler, showing my new design; and

Fig. 2 is a perspective view thereof.

I claim:

The ornamental design for a lawn sprinkler, substantially as shown.

COREY L. RUSSELL,
